CLAIM

The ornamental design for an earphone, as shown and
described.

DESCRIPTION

FIG. 1 is a top, front, right perspective view of a right-side
earphone showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top, front, left perspective view of a left-side
earphone showing an alternate embodiment of my new
design;

FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is a bottom view thereof.

The broken lines immediately adjacent to the shaded areas
define the bounds of the claimed design and form no part
thereof. The broken lines depicting the remainder of the
earphone show features that form no part of the claimed
design; all broken lines are for illustrative purposes only and
form no part of the claimed design.
